UNITED STATES PATENT OFFICE

HOWARD B. SEERY, OF LINCOLN PLACE, PENNSYLVANIA

FURNACE DOOR

Application filed December 23, 1930. Serial No. 504,354.

This invention relates to furnace doors for mill furnaces and its general object is to provide a furnace door that will not only withstand heat to a maximum intensity for a prolonged period of time without becoming warped or otherwise damaged, but in the event of damage thereto, can be repaired, rebuilt or replaced in an easy and expeditious manner by unskilled labor and in minimum time.

Another object of the invention is to provide a furnace door of the character set forth, that includes interfitting fire brick that face the heat of the furnace and can be associated with a frame and each other in a manner whereby casual displacement or removal of the brick from its frame is practically impossible.

Another object of the invention is to provide a furnace door that is reasonably simple in construction, inexpensive and easy to manufacture, and extremely efficient in operation and service.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a front elevation of the furnace door which forms the subject matter of the present invention.

Figure 2 is a rear elevation thereof.

Figure 3 is a sectional view taken approximately on line 3—3 of Figure 1 looking in the direction of the arrows.

Figure 4 is a sectional view taken approximately on line 4—4 of Figure 1, looking in the direction of the arrows.

Figure 5 is a sectional view taken approximately on line 5—5 of Figure 1.

Figure 6 is a perspective view of what I term the cap block of my door.

Figure 7 is a similar view of one type of block.

Figure 8 is a sectional view of another type of block used in the construction of my door.

Figure 9 is a similar view of a further type or shape of block.

Figure 10 is a sectional view taken approximately on line 10—10 of Figure 1.

Figure 11 is a sectional view taken approximately on line 11—11 of Figure 1.

Referring to the drawings in detail, the reference numeral 1 indicates a frame which may be cast in a single piece or made up of strips as shown, and this frame is substantially rectangular in formation, but is provided with a curved upper portion while the sides and bottom are straight. The frame as shown is made up of a lower or base strip 2, side strips 3 and an upper strip 4. The lower or base strip includes upstanding ends which together with the depending ends and the ends of the side strips are recessed, and these recessed ends are disposed in overlapping association and secured together. The strips 2, 3 and 4 are substantially L-shape in cross section.

Bridging the side strips and having their ends secured thereto are horizontal intermediate strips 5, while vertical intermediate strips 6 have their ends secured to the upper and lower strips and the vertical strips are secured intermediate their ends, intermediate the ends of the horizontal strips.

The securing means for the strips are in the form of rivets or the like and formed with the uppermost horizontal intermediate strip is a lug 7 adapted for the use of receiving a hook or like means of a hoisting device when it is desired to handle the door in removing or replacing the same as will be apparent.

Formed with the upper strip 4 is a flange 8 which acts in the capacity as a reinforcing means and has a tendency to prevent the door from warping, and formed with and rising from the upper end of the frame 1 are apertured ears 9 arranged in pairs. These ears may be termed lifting lugs and receive means for raising and lowering the door.

The lower edge of the frame 1 is provided with a depending flange 10 extending longitudinally of said edge and allows for the door

to fit in close to the door opening of the furnace.

The curved upper portion of the frame 1 has depending centrally and longitudinally thereof ribs which extend to the ends of the upper portion, while the lower portion of the frame 1 has formed therein a groove extending longitudinally thereof. The ribs and groove of the upper and lower portions of the frame 1 are adapted for a purpose which will be presently apparent, and the upper portion of the frame 1 is also provided with a slot 12 that is closed by a cap block which will be later described.

That part of the face of the door which forms the subject matter of the present invention is made up entirely of blocks as will be noted upon inspection of Figure 2, and these blocks are formed from heat resisting material and are of a particular construction so that they will have interlocking engagement with each other to prevent casual displacement thereof as well as a continuous heat resisting surface. In Figure 7 I have illustrated one type of block used in making this heat resisting surface and this type of block includes a body portion 13 having a longitudinally arranged groove 14 disposed in the top thereof, and the longitudinally arranged tongue 15 extending throughout the length of the bottom thereof.

Formed with and extending from one side of the body portion 13 is a substantially T-shaped projection 16 and this projection by being of the shape indicated provides recesses 17 for the purpose of accommodating the inwardly extending portions of the respective strips when the blocks are arranged in row formation as best shown in Figure 4.

The blocks as shown in Figure 8 are made in various sizes, but regardless of the size, each is provided with a groove in the top thereof and a tongue 19 depending from the bottom thereof. The top and bottom of the blocks as shown in Figure 8 and which for distinction are indicated by the reference numeral 20 are parallel and these blocks are utilized for filling purposes on the inner side of the intermediate strips as is also shown in Figure 4 as well as in Figures 3 and 10.

The block of the type as shown in Figure 9 is also made in various sizes and includes at least one inclined side such as indicated by the reference numeral 21, and this inclined side is provided with a groove 22. Depending from the bottom of the block as shown in Figure 9 and which for distinction is indicated by the reference numeral 23, is a tongue 24.

The cap lock is shown in Figure 6, and includes a curved upper portion 25, and a body portion 26 the latter having inclined ends as shown, and these ends as well as the bottom of the body portion is provided with a tongue 27.

In forming the heat resisting surface of the door with the blocks, it will be noted that blocks of the type as shown in Figure 8 are arranged along the lower portion of the frame 1, with the tongues thereof disposed within the groove of the lower portion as shown in Figure 4. Two layers of these blocks 20 are provided, thence the blocks as shown in Figure 7 are used in view of the vertical intermediate strips 6, the T-shape projections having their outer ends disposed in overlapping engagement with the vertical intermediate strips which are disposed in the recesses 17 as indicated in Figure 1. Cooperating with the blocks as shown in Figure 7, and disposed between the same are relatively small blocks of the type as shown in Figure 8, and these last mentioned blocks are arranged between the blocks as shown in Figure 7 in the outer spaces only, which are disposed between the outermost strips 6 and the side strips 3. The blocks as shown in Figure 7 and the relative small blocks are used until the horizontal intermediate strip 5 is reached, thence the blocks 20 are used until the surface is built above the strip 5, at which time the blocks are shown in Figure 7, as well as the relative small blocks are again used until the uppermost strip 5 is reached and this process is continued until the height of the blocks reach the curved upper portion of the frame 1, whereupon it becomes necessary to use blocks of the type as shown in Figure 9, and these blocks which are indicated by the reference numeral 23 are cut to fit the various spaces between the curved upper portion and the adjacent blocks. In building the heat resisting surface, it will be obvious that the tongues of the uppermost blocks are arranged in the grooves of the blocks below the same as shown in Figures 3, 4 and 10.

The ends of the slot 12 are inclined to fit the ends of the curved upper portion of the cap block, and when the remaining blocks are associated within the confines of the walls of the frame 1 and the strips, the cap block is positioned as shown in Figure 2 and held accordingly through the medium of pins 28 which rise from the top of the upper portion upon opposite sides of the slot 12, these pins 28 are received in bores provided in the curved upper portion 25. Slots are disposed in the pins 28 adjacent the upper ends thereof and these slots are adapted to receive wedge members 29 that engage the cap block as shown.

From the above description and disclosure of the drawings, it will be obvious that I have provided a furnace door that has a heat resisting surface made up of blocks composed of fire proof material due to the interlocking engagement of the respective blocks, it will be apparent that casual separation of the blocks will be reduced to a minimum and by utilizing the blocks, it will be further apparent that the door can be easily repaired or rebuilt, as

in the event that one or more blocks should become broken, they can be replaced in minimum time and with very little effort.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A furnace door comprising a frame, blocks formed from fire proof material and arranged in superposed relation with respect to each other, means for securing the blocks together and to the frame respectively, and a cap block for holding the first mentioned blocks in operative association.

2. A furnace door comprising a frame, blocks formed from fire proof material and arranged in said frame in superposed relation, said blocks being of various shapes and sizes for fitting engagement with each other and the frame, said frame having a slot in the upper portion thereof, a cap block having a portion arranged in said slot for holding the remaining blocks in operative association, and means for securing said cap block to said frame.

3. A furnace door comprising a frame including upper and lower strips, side strips secured to the upper and lower strips, intermediate strips secured to the upper and lower and to the side strips respectively, blocks having grooves arranged longitudinally thereof, tongues formed on said blocks and being received in said grooves in a manner whereby the blocks are disposed in superposed relation within the frame, some of said blocks having T-shape projections to accommodate portions of the strips, and a cap block secured to the upper portion of the frame for holding the remaining blocks in cooperative association.

4. A furnace door comprising a frame including upper and lower strips, side strips secured to the upper and lower strips, intermediate strips bridging and secured to the upper and lower and to the side strips and to each other respectively, blocks formed from fire proof material and being of various shapes and sizes for fitting engagement with each other and the spaces between the strips, said blocks being tongued and grooved for interfitting relation with respect to each other and the frame respectively, and a cap block secured to said frame for holding the remaining blocks in cooperative association.

5. A furnace door comprising a frame including a curved upper portion having a slot arranged centrally therein, ribs depending from the curved upper portion, a straight lower portion for said frame and having a groove disposed longitudinally therein, side

members, and a plurality of vertical and horizontal strips secured between the upper and lower and between the side members respectively, blocks formed from fire proof material and arranged in superposed relation, said blocks having grooves formed in the upper surface thereof, tongues depending from the lower surfaces of said blocks, the tongue of one block being arranged in the groove of its adjacent block, the lowermost blocks having their tongues disposed in the groove of the lower portion of the frame, the uppermost blocks having the ribs of the upper portion of the frame received in the grooves thereof, some of said blocks being shaped to receive portions of the strips for interlocking engagement therewith, a cap block for securing the remaining blocks in cooperative association, and having a portion disposed in the slot.

In testimony whereof I affix my signature.

HOWARD B. SEERY.
